UNITED STATES PATENT OFFICE

ALEX A. CLARKE, OF CHICAGO, ILLINOIS

CUTTER HEAD

Application filed June 21, 1928. Serial No. 287,311.

The present invention relates to cutter heads, and more particularly to heads adapted for use in portable cutting tools.

The primary object of the invention is the provision of a novel and efficient construction of cutter head having associated therewith a quickly insertible and removable cutter of relatively narrow width, and, therefore, relatively inexpensive to produce, thus permitting the blade to be discarded and thrown away after the same has become dull, and to be replaced expeditiously by a sharp blade as occasion for replacement may arise. The use of such blades materially reduces the weight of the cutter head and decreases the cost of blade upkeep.

The invention also aims to provide a cutter head equipped with a cutter blade of the character mentioned the mounting of the blade within the cutter head being such as to provide a firm seat for the blade. The latter thereby is held firmly in position in the cutter head, and is rigidly presented to the work during the cutting operation.

Furthermore, the invention contemplates novel locking means for holding the cutter blade in the cutter head, whereby to accomplish the aforesaid quick insertion and removal of the blade to and from the head, the replacement of the blades being easily effected without the use of special tools or other equipment.

In the construction of portable cutting tools there are two prime factors to be considered, viz., the security with which the parts of the tool are held together, and the weight of the driven parts. Due to the relatively small power unit which must be employed in tools of this character to reduce the weight of the tool to a minimum, and the desirability of driving the cutter heads at very high speed, which is particularly true of cutter heads such as disclosed herein, it is necessary that the moving parts be light in order that the power of the driving unit may be utilized in performing work, and not lost in developing and maintaining the momentum of heavy parts. Furthermore, due to the very high speed at which these devices are operated, it is essential that the parts be du-

rable and securely held. The cutter head hereinafter described may be constructed of relatively light material and at the same time provide a durable and secure structure.

Further objects and advantages of the invention will be apparent to those skilled in the art upon an understanding of a preferred embodiment of the invention as set forth in the following specification and the annexed drawings. It is to be understood, however, that this disclosure is for illustrative purposes only, and is not to be construed as unduly limiting the scope of the protection defined by the appended claims.

In the drawings—

Fig. 1 is a view in elevation of a cutter head embodying the present invention.

Fig. 2 is a sectional view on the line 2—2, Fig. 1.

Fig. 3 is a fragmentary face elevation of one of the cutter blades.

Having reference now in detail to the accompanying drawings, the numeral 11 designates the cutter head. This is generally cylindrical. It is free from sharp corners or edges and constitutes what is commonly known to the art as a safety head.

The cutter head 11 is mounted on a shaft 12 and is operated thereby from suitable driving connections.

The head 11 preferably is made of aluminum or some metallic alloy which is relatively light. In instances where the machine in which the cutter head is to be used is relatively heavy the head may be made of steel.

At equidistant points around the head 11 it is drilled to provide tangential sockets 13, the inner ends of which sockets are of slightly less diameter than their outer ends. These sockets are arranged in series longitudinally of the head 11, as shown in Fig. 1. The restricted inner ends of the socket 13 are screw-threaded and receive screw-threaded flanged bushings 14 the flanges 15 of which seat against shoulders 16 formed at the junction of the restricted inner ends and the enlarged outer ends of the sockets 13. These bushings 14 are also provided with kerfs 17 for receiving a screw-driver or similar tool for permitting rotation of the bushings when they are

introduced to and removed from the sockets 13.

The bushings 14 preferably are formed of steel or other hard and durable metal. They 5 occupy positions within the sockets 13 with their flanges 15 disposed a short distance below the outer surface of the head 11. Each of the bushings 14, the bore of which is screw-threaded, receives a standard machine screw 18, the heads of these screws snugly fitting the enlarged outer ends of the sockets 13.

After the several bushings 14 have been introduced to and properly fitted in their respective sockets, and before introduction of 15 the screws 18 to the bushings, a plurality of slots 19, one for each longitudinal series of the screws 18 to the bushings, a plurality of slots 19, one for each longitudinal series of the sockets 13, is milled lengthwise of the 20 face of the head 11. These slots 19 intersect the sockets 13, and are disposed in such relation to the bushings 14 that the side walls of the slots 19 and the flanges of said bushings form an obtuse angle. The milling operation 25 is continued until the edges of the bushings which are immediately contiguous to the slots 19 are milled away to form flat bearing surfaces 20 which extend across the bottoms of the slots 19, as best shown in Fig. 2.

30 A relatively narrow cutter blade 21 is received by each of the slots 19, the inner edges of said blades resting upon the hard flat bearing surfaces 20 which are afforded by the milled portions of the flanges 15 of the 35 bushings. These surfaces 20, therefore, constitute seats for the cutter blades 21, so that the latter are properly supported within the cutter head for rigid presentation to the work. Each of the cutter blades 21 is provided with a 40 plurality of equidistantly spaced semi-circular notches 22, one of these notches opening into the enlarged outer end of each of the sockets 13 when the cutter blades 21 are seated in the slots 19, and thereby being accessible 45 from the socket with which it communicates. The notches 22 are cut into the cutter blades 21 sufficiently deep to provide an inclined seat 23 at each notch. The inclination of these seats corresponds to the angular disposition 50 of the inner faces of the heads of the screws 18, and each of these notches receives the adjacent marginal portion of one of the screw heads. This interfitting of the heads of the screws 18 with the notches of the cutter blades 21 establishes a locking relation between the 55 screws and the cutter blades, and securely holds the blades in their respective slots 19. Obviously, when the screws 18 are removed so as to withdraw the heads thereof from the 60 notches 22 the cutter blades may be easily removed from the slots 19.

At points adjacent to the cutter blades 21, and intersecting the outer ends of the sockets 13, the face of the head 11 is milled lengthwise thereof to provide a plurality of con-

cave grooves 24. These grooves provide means for the escape of the shavings produced by the cutting blades when the cutter head is in operation.

A cutter head constructed in accordance 70 with the present invention affords a relatively simple form of head wherein cutter blades of relatively narrow width may be employed, so that the weight of the entire structure is materially reduced. The use of the bushings 75 related to the slots in which the cutter blades are mounted in the manner shown provides for these cutter blades a firm seat, and enables them to be rigidly presented to the work in the rotation of the head. Moreover, the 80 interlocking relation of the heads of the screws and the cutter blades insures proper retention of the cutter blades in their respective slots, but facilitates removal of the blades when they become dull, and their replacement by sharp blades when so required. The use of relatively narrow blades permits their manufacture at little expense, and when a blade has become dull it may be thrown 85 away with little loss. 90

I claim:

1. A cutter head of the class described having elongated slots across its peripheral face, cutter blades positioned in said slots, hollow screws secured in said head to constitute seats for said cutter blades, and additional screws threaded in said hollow screws to detachably hold the cutter blades locked against said seats. 95

2. A cutter head having elongated slots 100 extending across its peripheral face, hardened bearing seats provided at intervals in the bottoms of said slots, cutter blades arranged in said slots and positioned on said seats, and means secured to said seats for retaining said blades in said slots. 105

3. A cutter head having elongated slots extending across its face, hardened bearing seats provided at intervals in the base of said slots, cutter blades positioned in said slots, and screws retained by said seats and having their head portions overlapping the base portions of said blades to hold the latter on said bearing seats. 110

4. A cutter head having elongated slots cut in the peripheral face thereof, bushings secured in the head with the upper ends thereof forming a part of the base of said slots, cutter blades arranged in said slots, and screws threaded into said bushings and having their heads interfitting with the base portions of the cutter blades to detachably hold said blades in said slots. 115 120

5. A cutter head having elongated slots across its peripheral face, bushings secured in the head and projecting into said slots to constitute the bottom walls of the latter, cutter blades positioned in said slots and having their inner ends seated upon and supported by said bushings, said blades hav- 125 130

ing notches formed in the sides thereof adjacent to said bushings, and screws threaded into said bushings and having their heads seated in the notches of said blades to overlap the base portions of the cutter blades and thereby detachably hold the latter in said slots.

6. A cutter head provided with a plurality of tangential sockets, and also having elongated slots extending across its peripheral face and intersecting said sockets, bushings mounted in said sockets and extending into said slots to form the base thereof and provide supporting seats therein, cutter blades mounted in said slots and seated upon said bushings, and means secured to said bushings for detachably holding the cutter blades in said slots.

7. A cutter head provided with a plurality of tangential sockets, and also having elongated slots extending across its peripheral face and intersecting said sockets, bushings mounted in said sockets and extending into said slots to form the base thereof and provide supporting seats therein, cutter blades mounted in said slots and seated upon said bushings, and screws mounted in said bushings and having their heads in engagement with said cutter blades for detachably holding the cutter blades in said slots.

8. A cutter head provided with a plurality of tangential sockets, and also having elongated slots extending across its peripheral face and intersecting said sockets, bushings mounted in said sockets and extending into said slots to form the base thereof and provide supporting seats therein, cutter blades mounted in said slots and seated upon said bushings, said cutter blades having notches formed in the sides thereof adjacent to said bushings, and screws mounted in said bushings and having their heads interfitted with the notches of said blades for detachably holding the cutter blades in said slots.

45 9. A cutter head provided with a plurality of tangential sockets, and also having elongated slots extending across its peripheral face and intersecting said sockets, flanged bushings mounted in said sockets the flanges of which extend into said slots to provide supporting seats at the base thereof, cutter blades mounted in said slots and seated upon the flanges of said bushings, and screws mounted in said bushings and having their heads in engagement with said cutter blades for detachably holding the cutter blades in said slots.

10. A cutter head provided with a plurality of tangential sockets, and also having elongated slots extending across its peripheral face and intersecting said sockets, said slots being disposed in angular relation to said sockets, flanged bushings mounted in said sockets and having their flanges extending into said slots to provide supporting

seats at the base thereof, the portions of the flanges extending into said slots being cut away, cutter blades mounted in said slots and seated upon the cut-away portions of said flanges, and means cooperating with said bushings and said blades for detachably holding the latter in said head.

11. A cutter head provided with a plurality of tangential sockets, and also having elongated slots extending across its peripheral face and intersecting said sockets, said slots being disposed in angular relation to said sockets, flanged bushings mounted in said sockets and having their flanges extending into said slots, the portions of the flanges extending into said slots being cut away to provide supporting seats at the bases of said slots, cutter blades mounted in said slots and seated upon the cut-away portions of said flanges, and screws threadably engaged with said bushings and having their heads in engagement with the base portions of said blades for detachably holding the latter in said slots.

12. A cutter head provided with a plurality of tangential sockets, and also having elongated slots extending across its peripheral face and intersecting said sockets, said slots being disposed in angular relation to said sockets, flanged bushings mounted in said sockets and having their flanges extending into said slots, the portions of the flanges extending into said slots being cut away to provide supporting seats at the bases of said slots, cutter blades mounted in said slots and seated upon the cut-away portions of said flanges, said cutter blades having notches formed in the sides thereof adjacent to said bushings, and screws threadably engaged with said bushings and having their heads interfitted with the notches of said blades for detachably holding the cutter blades in said slots.

13. A cutter head having a socket in its peripheral face arranged tangentially to the axis of said head, and also having a slot in said face extending across the latter and intersecting said socket, a bushing seated in said socket and having a portion projecting into said slot to constitute the base thereof, a cutter blade seated in said slot and resting on said bushing to be supported by the latter, and means secured to said bushings for detachably holding the cutter blade in said slot.

14. A cutter head having a socket in its peripheral face arranged tangentially to the axis of said head, and also having a slot in said face extending across the latter and intersecting said socket, a bushing seated in said socket and having a portion projecting into said slot to constitute the base thereof, a cutter blade seated in said slot and resting on said bushing to be supported by the latter, and a screw threadably engaged with said bushing and having its head interfitted

with the cutter blade for detachably holding the latter in said slot.

15. A cutter head having a socket in its peripheral face arranged tangentially to the axis of said head, and also having a slot in said face extending across the latter and intersecting said socket, a flanged bushing seated in said socket and having a portion of its flange projecting into said slot to constitute the base thereof, a cutter blade seated in said slot and resting on the flange of said bushing to be supported by said flange, said cutter blade having a notch formed in the side thereof adjacent to said bushing, and
10 15 a screw threadably engaged with said bushing and having its head interfitted with the notch of said blade for detachably holding the cutter blade in said slot.

16. In a device of the class described, a
20 supporting member, pairs of screws adjustably threaded in said supporting member, one of the screws of each pair being threaded into the other, and a cutter blade located and fixedly held in place by the threaded
25 engagement of said pairs of screws, one screw of a pair constituting a seat for locating the associated cutter blade.

In testimony whereof I have hereunto subscribed my name.
